UNITED STATES PATENT OFFICE.

JOSEPH H. BECKWITH, OF LOCKESBURG, ARKANSAS.

SLIDING DOOR.

Application filed July 16, 1925. Serial No. 44,058.

This invention relates to improvements in sliding doors and windows and more particularly to that type in which two vertically 5 slidable sections are connected so as to balance each other and provide for lowering of one section when the other section is elevated, and vice versa.

One of the objects of the present invention is to provide a door or window structure 10 of the type referred to above so constructed that the sections thereof will be equally balanced in a manner to insure of smooth and even sliding adjustment of the sections in opening and closing the door.

Another object of the invention is to so 15 construct the door that the sliding movement of the sections thereof will be limited when they have reached their open or their closed position, thereby preventing any such 20 movement of the sections beyond open and closed position which would be liable to cause disarrangement of the connections provided for the sections.

Another object of the invention is to provide 25 novel means whereby the connections of each section may be adjusted so as to insure perfect balancing of the sections with relation to each other and thus insure of even movement of the sections when ad- 30 justed.

In the accompanying drawings:

Figure 1 is a view in elevation of a sliding door constructed in accordance with the 35 present invention, parts being broken away and parts being shown in section to better illustrate the invention, the sections of the door being in closed position.

Figure 2 is a vertical sectional view taken 40 substantially on the line 2-2 of Figure 1, looking in the direction indicated by the arrows.

Figure 3 is a detail horizontal sectional 45 view taken substantially on the line 3-3 of Figure 1, looking in the direction indicated by the arrows.

Figure 4 is a vertical sectional view on the 50 line 4-4 of Figure 3, looking in the direction indicated by the arrows.

The invention may find embodiment in 55 doors for elevators, warehouses, garages, etc., or the principles thereof may be embodied in the construction of windows of various

types. In the embodiment of the invention illustrated in the drawings, the numeral 1 indicates in general the jamb of the door 55 frame, and the numeral 2 indicates in general the lintel of the frame, the sill of the frame being indicated by the numeral 3. The jamb 1 preferably comprises a hollow structure including spaced walls 4 between 60 the edges of which, which are presented at the door opening, there is arranged a connecting or partition wall 5 which, together with said edge portions of the wall 4, constitutes a guide 6 for the upper section of 65 the door, which section is indicated in general by the numeral 7. A similar partition wall 8 is arranged between the walls 4 and the lower portion of the jamb and each of the walls 8 occupies a plane spaced inwardly 70 a short distance from the plane occupied by the respective wall 5, the said walls 8 and the walls 4 constituting a guide 9 for the lower section of the door, which section is indicated in general by the numeral 10. The 75 floor of the building of which the door constitutes a part, is indicated by the numeral 11, and the floor is provided at the sill 3, with a slot 12 to permit of downward sliding movement of the lower section 10 of the 80 door. If found desirable or expedient, a housing 13 may be provided beneath the floor 11 to accommodate the lower section 85 of the door when said section is in its lowered or open position, but, in any event, the walls 8 will preferably be extended below the floor line so as to properly guide the lower section of the door when the same is lowered. The lintel 2 comprises a lintel proper which is indicated by the numeral 14 90 and which defines the upper side of the doorway, and preferably, the walls 5 are extended above the said lintel proper to a sufficient height to suitably guide the upper section of the door when the same is slid upwardly to 95 open position.

The door sections 7 and 10 may be of any construction found suitable, depending upon the size of the door as a whole, and the character of the building or other structure in 100 which it is to be installed. In the illustrated embodiment of the invention, the upper section 7 of the door comprises end stiles 15, a top rail 16, a bottom rail 17, and

a panel 18 arranged within the frame constituted by the stiles and rails. In a like manner, the lower section 10 comprises end stiles 19, top and bottom rails 20 and 21, and 5 a panel 22. Therefore, the stiles 15 of the upper section work slidably in the guides 6 of the jamb 1, and the stiles 19 of the door section 10 work slidably in the guides 9 of the said jamb. It will be observed by 10 reference to Figure 2 of the drawings, that the guides 6 and 9 are located in the same vertical plane so that the door sections 7 and 10 likewise occupy a common plane. In order that the doors may be connected for sliding movement in unison and 15 may balance each other, a cable or other flexible element 23 is secured at one end, as at 24, to the outer edge of each stile 15 of the upper section 7 of the door and is led 20 upwardly along the inner side of the respective wall 5 of the lintel 14 and over a pulley 25 mounted in the wall 5 near the upper end of the upwardly extended portion thereof. The cable 23 is led downwardly from 25 the pulley 25 and connected to the respective stile 19 of the lower door section 10 through the medium of an adjustable connection 26 which is best illustrated in Figures 3 and 4 of the drawings.

30 The stiles 19 of the lower door section 10 are formed with grooves 27 in their outer edges to accommodate the stretches of the respective cable 23, and the outer edge of each stile is further formed with a recess 28 to 35 accommodate the connecting device 26, as clearly shown in Figures 3 and 4 of the drawings. The said device comprises a sheet metal housing 29 secured in place within the upper portion of the recess 28 40 through the medium of screws or other suitable fastening elements 30. The upper end of the housing or casing 29 abuts against the upper end of the recess 28, and the casing is open at its side which is presented 45 toward the wall 8 of the respective jamb. The casing at its lower end is closed by a bottom piece 31, and the said bottom piece is formed with an opening 32 through which is fitted a threaded shank 33 at the lower 50 end of an anchoring member 34 preferably of the cross sectional contour shown in Figure 3 of the drawings. The anchoring member 34 is formed with an opening 35 located near its upper end and with an opening 36 55 located at its intermediate portion, and the lower end of the respective cable 23 is fitted through the opening 35 from one side of the member, thence led downwardly through a groove 37 formed in the other side of the member, and thence threaded through the 60 opening 36, a ring 38 being secured about the member below the opening 36 and anchoring the lower end of the cable. A nut 39 is threaded onto the threaded shank 65 33 of the anchoring member 34 and bears

against a washer 40 which, in turn, engages the under side of the bottom piece 31 of the casing 29. At this point it will be evident that by applying a wrench to the nut 39, the respective cable 23 may be slackened or taken 70 up so that should it be found that the door sections are not evenly hung, this may be compensated for by adjusting one or the other of the connecting devices.

From the foregoing description, it will be 75 understood that by raising the upper door section 7 or lowering the lower section 10, the sections being in the closed position shown in Figures 1 and 2 of the drawings, the other section will be moved in the opposite direction until the lower edge of the upper section is, in the full open position of the sections, substantially flush with the lintel proper 14, and the upper edge of the lower section is substantially flush with the 80 sill 3. Movement of the door sections to closed position may be effected by lowering the upper section or raising the lower section.

As a convenient means for adjusting the 85 door sections, a cable or other flexible element 41 is preferably connected at its ends, as at 42, to the upper rail 15 of the upper section 7 and passed over pulleys 43 at the top of the lintel of the door frame, and thence downwardly with its intermediate portion passing through an eye 44 upon the lower rail 17 of the said upper door section. By pulling down upon the stretches 90 of the flexible element 41, which stretches extend between the eyes 43 and 44, the upper section of the door will be slid upwardly and the lower section will, by gravity, assume a lowered position.

By reference to Figure 1 of the drawings, 105 it will be observed that when the door sections are in closed position, the upper corners of the lower section will abut against the lower ends of the respective walls 6 of the jamb, and likewise, the upper edge of the 110 said lower section will abut against the lower edge of the upper section.

Having thus described the invention, what I claim is:

1. In combination with a frame including 115 jambs, each of the jambs comprising transversely spaced walls and upper and lower partitions connecting the spaced walls, the lower partition being inset from the upper partition and upper and lower closure sections 120 slidable in the jambs, the lower section extending between the lower partitions and limited in its upward movement by contact with the lower ends of the upper partitions.

2. In combination with a frame including 125 jambs, each of the jambs comprising transversely spaced walls and upper and lower partitions connecting the spaced walls, the lower partition being inset from the 130

upper partition, upper and lower closure sections slideable in the jambs, the lower section extending between the lower partitions and limited in its upward movement by contact with the lower ends of the upper partitions, guide pulleys at the top of the upper partitions, flexible elements passing over said pulleys and connected at one end to the upper closure section, an anchoring member

connected to the other end of each of the flexible elements and formed with a threaded shank, a housing let into each of the stiles of the lower closure section and having its bottom apertured to receive the threaded shank and a nut on each of the threaded shanks to adjust the flexible elements.

In testimony whereof I affix my signature.
JOSEPH H. BECKWITH. [I. S.]
